STYLUS FOR MAKING SOUND RECORDS

Walther Hesse, Aachen, Germany

Application October 15, 1932, Serial No. 637,961
In Germany October 29, 1931

3 Claims. (CL. 274—38)

This invention relates to a stylus for making sound records, the point of which has chisel-like cutting edges.

An object of this invention is the provision of a stylus having a cutting point which will have no natural vibration while the sound records are being made.

The above and other objects of this invention may be realized by providing a stylus having a symmetrical cutting point portion which is wider at its base than the shank of the stylus, at least two cutting edges of said cutting point portion forming with each other an angle of substantially 90°.

15 The invention will appear more clearly from the following detailed description when taken together with the accompanying drawing showing preferred embodiments of the inventive idea.

In the drawing:

20 Figure 1 shows in side elevation a stylus of the type used in prior art.

Figure 2 is a bottom plan view of the stylus shown in Figure 1.

25 Figure 3 shows in front elevation another stylus of the type used in prior art.

Figure 4 is a bottom plan view of the stylus shown in Figure 3.

Figure 5 is a front elevational view of a different stylus known in prior art.

30 Figure 6 shows in front elevation a stylus made in accordance with the principles of the present invention.

Figure 7 shows in side elevation the stylus illustrated in Figure 6.

35 Figure 8 is a back view of the stylus illustrated in Figure 6.

Figure 9 is a section along the line A—B of Figure 7.

40 Figures 10, 11 and 12 are front view, side view and back view, respectively, of a different stylus.

Figure 13 is a section along the line C—D of Figure 11.

45 Figures 14, 15 and 16 are front view, side view and back view, respectively, of another stylus.

Figure 17 is a section along the line E—F of Figure 15.

50 Figures 18, 19 and 20 are front view, side view and back view, respectively, of a different stylus.

Figure 21 is a section along the line G—H of Figure 19.

55 Figures 22, 23 and 24 are front view, side view and back view, respectively, of a yet another stylus.

Figure 25 is a section along the line J—K of Figure 23.

The point of the known styluses of this kind forms, as shown in elevation and bottom plan views in Figs. 1 to 4 a three-sided or four-sided pyramid. Styluses are also known which, as shown in Fig. 3, are formed by an equilateral triangular cutting plate bevelled at the edges on both sides, which plate is detachably connected to the shank of the stylus by a screw. As in the known styluses with pyramidal point the base of the point corresponds to the cross section of the shank, these styluses are not very rigid. The same applies to the styluses with a triangular cutting plate fixed on the shank by screws, especially as this plate is relatively thin and its intersecting cutting edges form an angle of only 60°. These known styluses consequently vibrate considerably when cutting sound grooves in records of hard material, such as hard rubber and metal, and cut and tear chips from the record. The sound records cut in hard record plates by means of these known styluses are consequently not sharp and clean so that disturbing secondary noises and considerable distortion of tone occur when such records are played. These objections are overcome by employing the styluses according to the invention.

The invention consists substantially in that the point worked from the material of the circular or non-circular shank is wider at its base than the shank of the stylus. When cutting sound grooves even in hard records by means of the stylus according to the invention, all detrimental vibrating of the stylus is avoided, owing to the special shaping of its point, and consequently a very clean cut is produced because a continuous chip is cut from the record. Records produced with this stylus therefore give a reproduction without disturbing secondary noises and distortion of tone. Moreover, by the shape of the point of the shaft, convenient flat gripping surfaces are produced thereon, which facilitate the correct insertion of the stylus into the holder of the sound box, which is very important for making records. Owing to the flat shape of the point the new stylus also presents the advantage, that it can be provided by means of colour or in some other manner with clearly visible markings on its point to further facilitate the proper fitting of the stylus in the holder.

The bevelled lateral edges of the point of the stylus preferably form an angle of about 90°. A stylus constructed in this manner produces a particularly clean cut.

Experiments have shown that it is particularly advantageous for the point to have either a flat

surface both on its front side and also on its rear side, or a flat surface on one side and a recessed surface on the other side.

Five embodiments of the invention are illustrated by way of example in Figs. 6 to 25 of the accompanying drawing.

In all five forms of construction a point *a*, *b* having chisel-shaped edges is worked from a shank *c*, which point is wider at its base than the shank *c* so that the point projects beyond the shank on each side. The two cutting edges *a* and *b* of the point form an angle of approximately 90° and are undercut ground or bevelled from the front towards the rear. The examples illustrated differ chiefly only as regards the shape of the surfaces on the front and rear sides of the points of the different styluses.

In the construction shown in Figs. 6 to 9 the point of the stylus has flat surfaces *d* and *e* on its front and rear sides, which surfaces are slightly inclined relative to the longitudinal axis of the shank *c*.

In the construction illustrated in Figs. 10 to 13 the point of the stylus only has a flat surface *g* slightly inclined to the longitudinal axis of the shank *c* on its rear side, whereas on its front side it is provided with a hollow surface *f*, which is formed by two surfaces inclined towards one another to form an obtuse angle.

In the form of construction according to Figs. 14 to 17 the point has on its front side a flat surface *h* slightly inclined to the longitudinal axis of the shank *c* and on its rear side a recessed surface *i* corresponding to a portion of the surface of an imaginary cylinder extending transversely to the longitudinal axis of the shank.

According to the construction shown in Figs. 18 to 21 the point has on its front side a flat surface *k* slightly inclined to the longitudinal axis of the

shank and on its rear side a hollow surface corresponding to an imaginary cylinder, the longitudinal axis of which is parallel to the longitudinal axis of the shank.

The stylus illustrated in Figs. 22 to 25 has on its front side a flat surface *m* slightly inclined to the longitudinal axis of the shank, and on its rear side a recessed surface *n* corresponding to a portion of the surface of an imaginary ball.

I claim:—

1. A stylus for making sound records, comprising a shank having a cutting point and cutting side edges with flattened and converging front and rear faces, said cutting side edges being formed by an upwardly and rearwardly bevelled end of the stylus, forming a blunt V-shaped cutting edge, the stylus at the end of said bevels being laterally enlarged.

2. A stylus for making sound records, comprising a shank having a cutting point and cutting side edges with flattened and converging front and rear faces, said cutting side edges being formed by an upwardly and rearwardly bevelled end of the stylus, forming a blunt V-shaped cutting edge, the stylus at the end of said bevels being laterally enlarged, the converging rear face being inwardly and outwardly curved.

3. A stylus for making sound records, comprising a shank having a cutting point and cutting side edges with flattened and converging front and rear faces, said cutting side edges being formed by an upwardly and rearwardly bevelled end of the stylus, forming a blunt V-shaped cutting edge, the stylus at the end of said bevels being laterally enlarged, said flattened front face having a lower portion which extends outwardly away from said rear face.

WALTHER HESSE.
